UNITED STATES PATENT OFFICE.

WILLIAM RICHARD WALKEY, OF WESTMINSTER, LONDON, ENGLAND.

APPARATUS FOR THE STERILIZATION OF FLUIDS.

1,199,642.

Specification of Letters Patent. Patented Sept. 26, 1916.

Application filed April 8, 1915. Serial No. 19,896.

To all whom it may concern:

Be it known that I, WILLIAM RICHARD WALKEY, a subject of the King of England, residing in Westminster, London, England, 5 have invented certain new and useful Improvements in Apparatus for the Sterilization of Fluids, of which the following is a specification.

This invention relates to apparatus where- 10 in is employed ultra-violet light for the sterilization of milk, beer and other liquids, more particularly opaque liquids, such as milk.

The object of the present invention is to 15 provide a sterilizing apparatus, the efficiency of which shall be considerably greater than apparatus hitherto employed and to effect this the surface over which flows the fluid to be sterilized, is arranged in a particular 20 manner and is of a particular character, such as will afford the best possible concentration of the light-rays upon the fluid.

Thus, according to this invention, a sterilizing apparatus comprises in combination a 25 source of ultra-violet light and a stationary member providing a surface over which the fluid to be sterilized may flow in contact by adhesion or surface tension under the action of gravity, (sometimes referred to as capillary 30 attraction) in a thin film to be acted upon by the said ultra-violet light-rays, characterized by the said surface being corrugated in a vertical plane and also curved as a whole so that the rays of light from the 35 source strike the fluid in a normal or substantially normal direction or at least are inclined away from the normal to a substantially less degree than would be the case if an uncurved surface were employed in place 40 of the curved surface. Preferably means are also provided for maintaining a circulation of air over the said surface.

According to one particular embodiment 45 of the invention there is a plurality of surfaces curved as above described and arranged symmetrically around the source of light. More particularly the said surfaces are curved apart from their corrugations only in one plane, generally in a horizontal plane. 50 The invention will be more clearly understood by reference to the following description taken in connection with the accompanying drawings which illustrate a preferred embodiment thereof, and in which— 55 Figure 1 is an elevation, partly in section,

of the apparatus; Fig. 2 is a plan of Fig. 1, parts being removed for clearness; Fig. 3 is a plan of one of the surfaces having a convenient curvature; Fig. 4 is a section on line 4—4 of Fig. 3. Figs. 5 and 6 diagrammatically illustrate modified forms of portions of the apparatus.

Like letters indicate like parts throughout the drawings.

The main frame of the apparatus consists 65 of vertical supports A tied at A¹ at the top and bottom. Between each adjacent pair of supports A is a swinging side B, each of which is identical so that a description of one will suffice for all. The important feature of the sides is that they shall be curved as shown in plan in Figs. 2 and 3. They may constitute swinging sides by being hinged at B¹ to the supports A and, if desired, any convenient form of clip may be 70 employed to hold them in place. Supported above the sides B is a tank C having holes C¹ disposed close to the upper edge of the sides B so that fluid may fall by gravity from the tank C on to the sides. The holes C¹ are so 75 dimensioned that the fluid passes on to the side B in a thin film and by adhesion under the action of gravity flows over the surface on the corrugations.

Arranged centrally in the tank C is a funnel C² which opens the interior of the apparatus to the outer surrounding atmosphere and serves as an uptake for the exit of any ozone which may be formed and also for the air as it becomes slightly heated during 80 the operation of the apparatus. Thus a circulation of air is maintained which keeps the air in the apparatus cool and pure.

Within the apparatus is a source of ultra-violet light which may conveniently consist 85 of two mercury vapor lamps D suspended from the support A. The curvature of the sides may be such as to, as closely as possible, approximate that of a circle struck from a center approximately coinciding with the 90 position of the source of light. Thus, referring to the dotted lines in Fig. 3, assuming E to be the lamp, it will be seen that while a ray, diagrammatically shown at E¹, strikes the curved surface B substantially in 95 a normal manner, it strikes the plane surface F in an oblique direction, while similarly a ray, such as E², far more nearly approximates to a normal ray in relation to the curved surface B than it does to the 100 105 110

plane surface diagrammatically shown at F. It has been found convenient in practice to curve the surface B on either the lines of a parabolic curve or of a circle having a 5 somewhat larger diameter than the diameter of the apparatus, which latter may conveniently be 12-18 inches internally. The fluid drains from the sides B into a receptacle G from which it is removed by a drain-
10 pipe G¹.

Although the invention has been described in detail it is not limited to the particular construction illustrated as that is shown merely as one convenient arrangement of 15 the various parts. Thus, the surfaces B may be curved in their length from top to bottom as diagrammatically shown in Fig. 5 to increase the benefit obtained from the invention. Further, a fan H may be employed in 20 conjunction with the funnel or uptake (see Fig. 6) to cause a continuous flow of air through the apparatus and to remove positively the ozone and warm air and at the same time more effectively to keep the appa-
25 ratus cool.

What I claim as my invention and desire to secure by Letters Patent is:-

A sterilizing apparatus comprising in combination, a source of ultra-violet light, a plurality of hinged members arranged 30 around the source of light each of said members having a surface which is curved so that it presents a concavity to the source of light and has on it corrugations which are transverse to its vertical axis, an annular 35 container surmounting the said members and having a central chimney-like extension and peripheral orifices communicating with the inner faces of the said members for the purpose described, and means to remove the 40 fluid after it has been sterilized from the lower edges of the said members.

In testimony whereof I have signed my name to this specification in the presence of two subscribing witnesses.

WILLIAM RICHARD WALKEY.
